UNITED STATES PATENT OFFICE.

WILLIAM FLETT, OF HYDE PARK, MASSACHUSETTS.

NUMBERING DEVICE.

982,263.

Specification of Letters Patent. Patented Jan. 24, 1911.

Application filed September 9, 1908. Serial No. 452,317.

To all whom it may concern:

Be it known that I, WILLIAM FLETT, a citizen of the United States, residing at Hyde Park, Massachusetts, have invented 5 certain new and useful Improvements in Numbering Devices, of which the following is a specification.

This invention has to do with the numbering of articles bearing checks, coupons, or 10 similar devices, and more particularly to the numbering of the parts of railway mileages or tickets. Work of this sort requires the printing of tickets in various parts and usually involves an intricate system of numerical series upon the perfection of which a great deal depends, and which must be guaranteed against error. It is of paramount importance, therefore, that the numbering mechanisms are positive and accurate 15 rate, as any sudden jump or jerk is liable to cause an actuation and give a skip in the numbers and a break in the series. It is also necessary, where a plurality of numbering devices are to be worked together, that 20 their actuation be simultaneous and uniform. In the production of railway tickets and mileages it is frequently necessary to have several series, and as the production of tickets is often required on short notice, or 25 under the stress of large orders, the means of multiplication or expansion of these systems is necessary in order to cope with the situation. It is, moreover, desirable to have in these systems the possibility of relative 30 arrangement according to some predetermined scheme, so that safeguards may be set against counterfeiting and the detection of such counterfeiting made possible. To the end, therefore, of providing mechanisms 35 for the production of such tickets, mileages, etc., which shall be capable of the various adjustments and combinations above indicated, and which will have motions so positive and uniform as to afford safe control 40 for the advancing of the numbering series, and to the production of various improvements in the serial parts of presses for such work, I have devised my present invention, 45 which I will more fully disclose in the following specification.

In the drawings, which form a part of this specification, there is set forth an embodiment illustrative of my invention, and showing various improvements in structure 50 and operation.

Throughout the specification and drawings, like reference numerals are employed to indicate corresponding parts, and in the drawings, Figure 1 shows the impression cylinder and adjuncts of a rotary press. 60 Fig. 2 a central section looking from right to left, Fig. 1, with some of the moving parts in elevation and some broken away. Fig. 3 is a view of a numbering head with operating device. Fig. 4 a sectional view of 65 parts shown in Fig. 3, on the indicated line 4—4, Fig. 6. Fig. 5 is a sectional view looking from left to right, Fig. 3, on line 5—5. Fig. 6 is a transverse sectional view of the numbering head just inside of the end 70 plates. Fig. 7 is a side view of a ratchet mechanism for the disks. Fig. 8 is an end view of said ratchet mechanism on the line 8—8, Fig. 4. Fig. 9 is a side view of head 75 showing the locking pawls. Fig. 10 is a view of locking pawls for the ratchets. Fig. 11 is a plan view of the operating pawls and 80 their supporting arms. Fig. 12 is a view of a segmental gear for actuating the pawl supporting arm. Fig. 13 is a side view of 85 the gear shown in Fig. 12. Fig. 14 (Sheet 2) is a detail of the inking roll oscillator, line 14—14 of Fig. 2. Fig. 15 shows a section of the impression cylinder with a lifting 90 plate.

1 is the impression cylinder of a rotary press, journaled on the frame 2 and driven by a gear 3 on a power shaft 4. The pinion 3 meshes with a gear or circular rack 5 set on the cylinder 1 near one edge thereof, as 95 appears to the right of Fig. 2.

6 indicates a portion of the plate cylinder between which and the cylinder 1 the web of paper passes in receiving the first impression. 95

7 is a gear on the shaft 8 of the cylinder 1 with which the pinions 11 and 12 on vibrator shafts 13 engage in staggered relation. By this arrangement, I am able to drive all 100 of the shafts 13 at equal rates by teeth 9 on the gear 7. The shafts all have bearings 10 for their inner ends adjacent to the gear 7 and suitable bearings 14 for their outer ends.

26 is a title cylinder mounted in a suitable bracket 21, and having suitable connections, rolls and ink feed. The ink feed is shown broken away in Fig. 1, but is similar to that indicated in the tint cylinder 30 which lies 110 next to it and which is indicated in Fig. 1. 105

the tint cylinder 30 is mounted in a bracket 31, and has suitable connections, rolls, and ink feed.

40 are twelve number head shafts arranged in pairs in six brackets 41, each shaft 40 having a bearing 42 yieldingly held down by a spring 43.

17 are gears on the shafts 40 which are driven by the gear 15 on a cylinder 1 to rotate the shafts 40.

50 is a shaft carrying stub numberers suitably mounted in a bracket 51 and having suitable connections, rolls and ink feed.

60 is a shaft for the serial numberer journaled in a bearing 62 yieldingly held down in a bracket 31 by a spring 63.

On an extension frame 16 next to the cylinder 1 is mounted a perforator shaft 70 having a suitable perforator for providing the 20 transverse perforations between coupons. The shaft 70 is journaled in a bearing 71 yieldingly held down by a spring 72.

80 is a slitter shaft having suitable slitters for cutting and trimming the main web 25 into ticket widths.

90 is a shaft carrying parallel perforators, for making longitudinal perforations, and having its ends journaled in bearings 91 yieldingly held down by springs 93 in brackets 92. The transverse perforators, slitters and longitudinal perforators are all driven by a suitable train of gears from the cylinder 1.

For each of the pairs of number heads and 35 for the title cylinder 20, tint cylinder 30, stub numberer 50 and serial numberer 60, I have provided vibrating ink rolls 100 journaled in the several brackets. (See Fig. 2.) The shafts 100 of the rolls 100 have at one 40 end a spool 102 within the flanges of which is located a disk 103, eccentrically mounted on the shaft 13, by which is imparted to the rolls 100 an even transverse reciprocation which will evenly distribute the ink. In 45 delivering ink to the numbering heads on the shaft 40 the roll 100 receives it from a feed 101 and passes it to a distributing roll 104, from which the heads take it.

On each of the twelve shafts 40 are arranged one or more numbering cylinders according to the number of tickets or mileages to be run in the web. In Fig. 2, two of such cylinders are shown, being given a general number 44. Each number cylinder comprises four number heads.

45 are operating rock shafts for the number heads of the cylinders 44, being arranged in sets of four arranged about the shafts 40 and supported parallel thereto in bearing 60 collars 46 set on the shaft 40. At one end, as shown to the right of Fig. 2, and the left of Fig. 3, each of these shafts is provided with an operating crank 47 having a roller 48, and adapted to be rocked thereby on the 65 actuation of a tapered sleeve 49 which is

loose on the shaft 40. The cranks 47 are held down about the shaft 40 by a band of springs 250 against which the tapered sleeve 49 acts in throwing up the arms.

110 is a rider fast to the collar 49, and 120 70 is a similar rider near the opposite end of the shaft 40, but fast on the shaft itself. These riders 110 and 120 are engaged by lifting plates 130 and 140, lying upon the periphery of the cylinder 1, but bolted to the 75 ends thereof through their flanges 131 and 141 respectively. These plates have tapered ends 132 and 142, which act as cam surfaces to make the lift of the riders smooth and easy. The plates 130 and 140 are divided 80 midway of their length and their flanges 131 and 141 are slotted so as to permit their adjustment for timing the rise and fall of the shaft 40 to exactly the periods required. The rider 120 and the plates 140 are smooth, 85 but the rider 110 is provided with a fin 111 which runs in a groove 133 in the plates 130. This groove runs inwardly from its outer edge then outwardly again in a gradual curve, allowing it an even cam action with 90 the fin 111 of the rider 110. By forming these bearing plates of proportionate length and in sufficient number the numberer shafts 40 may be raised and the heads of the cylinders actuated at any given periods of the 95 cycle of the press. Thus with a press capable of printing one thousand mileage coupons with stubs in one revolution, one pair of plates 130, 140, would be proper for the single mileage. To print five hundred mile 100 mileages on the same press, two sets of plates oppositely disposed in pairs on the cylinder 1 would be employed, thus producing two mileages per cylinder revolution. Correspondingly, for two hundred and fifty 105 mile tickets, four such pairs of plates, 130 and 140, would be used and four mileages per revolution produced.

Referring particularly to Sheet 3, it will be seen that the numbering cylinder 44 comprises a pair of flanges 150 set on the shaft 40 by set screws 151. Between these flanges 150 run four short shafts 160, on which are rotatably mounted the number disks 170, 171, 172, 173 and 174, for printing respectively 110 the units, tens, hundreds, thousands, and ten thousands. Each of these sets of disks with their operating mechanisms constitute a number head. Each one of the disks 170-174 is provided with operating ratchets 180, 181, 182, 183, 184, each having nine teeth 190 of equal depth and a pocket 191 at the tenth tooth. The pockets are of decreasing depth in each disk beginning with the unit disk.

200 and 201 are a pair of arms set on the shaft 160, which passes through openings 202, so that the arms may freely rock thereon. The ends of the arms 200 and 201 are connected by a web 203.

204 is a pawl body pivotally mounted on a bar 206, but held toward the ratchet wheels by the spring 207.

170', 171', 172', 173', 174', are pawl teeth of gradually decreasing length.

210 is a segmental gear keyed to the shafts 45, and having its teeth meshed with a corresponding gear segment on the end of the arm 201, opposite to the web 203. When, therefore, the shaft 46 is rocked by the arm 47, the segmental gear 210 will move the arm 201, raising the pawl 204 so that it will engage the next tooth in the ratchet train. As the pawl teeth 170' to 173', inclusive, are of gradually decreasing length, it will be seen that when the number disk 170 has been actuated nine times the pawl tooth 170' will then drop into a pocket 191, allowing the pawl tooth 171' to drop into engagement with the ratchet on the number disk 171, which will advance the disk 171 one number, and at the same time carry the ratchet tooth 170' past the pocket 191 in the ratchet wheel of the disk 170 and let it engage the adjacent ratchet tooth 190 in which position the pawl 171' will be held out of contact with the wheel 181. The ratchet tooth 170' being longer than the ratchet tooth 171', the ratchet tooth 170' will continue to actuate the number disk 170 until it has made a complete revolution and the pocket 191 is again presented to the pawl tooth 170', when the pawl tooth 171' will again be allowed to drop into engagement with the ratchet on the number disk 171. The number disk 171 will, therefore, be again actuated, and so on until the pocket 191 has come around on the ninth actuation to a position side by side with the pocket 191 in the ratchet wheel of the number disk 170. In this position the ratchet tooth 170' and the ratchet tooth 171' will both drop sufficiently to allow the ratchet tooth 172' to engage the first tooth on the ratchet wheel 182 of the number disk 172, which will be accordingly advanced one numeral. In this way, the units, tens, hundreds, etc., will be successively brought forward in series.

220 is a catch pawl for holding each number disk from running ahead, being yieldingly held in engagement by a spring 221 with the teeth of the ratchets of each number disk. The catch pawl 220 is pivoted on a cross bar 222 and the springs 221 are formed as spring teeth on a comb 223 which is screwed to a cross bar 224.

230 indicates a suitable folder operated by a link 231, driven by a crank on a shaft 232 adjustable in a slot 233 on which a gear 234 is driven by the rack 5 on the impression cylinder 1.

240 are feed rolls for passing the tickets in a continuous strip up to the folder 230.

Following the web of paper, indicated by the line α , through my device, it will pass

first between the plate cylinder 6 and the impression cylinder 1, then following said impression cylinder 1, it will pass under the title cylinder 20, the tint cylinder 30, then successively under the numbering cylinders 70 on the twelve shafts 40, then under the stub numberer which is intermittently actuated at the proper intervals to print the proper number of stubs, then under the serial numberer. At this point it leaves the impression cylinder 1, and, passing under a tension roll 69, meets the transverse perforators 70, then under the slitters and trimmers 80 reaches the longitudinal perforators 90. From the perforators 90 the tickets go in strips to the feed rolls 240 which pass them up into the folder 230. As soon as the tail of one ticket passes the first number shaft 40 the plate 130 comes up to successively raise each shaft 40 and actuate the rock shafts 45 to advance simultaneously the number heads 44 of each number cylinder 40 one unit.

It will be seen that the number of numbering cylinders on each shaft 40 may be varied so that one or two or even five tickets 90 may be run simultaneously.

What I therefore claim and desire to secure by Letters Patent is:—

1. In a rotary press, a plurality of movably mounted numbering shafts, means for rotating said shafts, an adjustably mounted numbering cylinder on each shaft, a plurality of intermittently actuated rotatable numbering heads in each cylinder and means for simultaneously raising said shafts and actuating said numbering heads while raised from the work.

2. In a rotary press, an impression cylinder, a plurality of shafts, numbering cylinders on said shafts yieldingly held against said cylinder, a plurality of intermittently actuated rotatable numbering heads in each cylinder, means for rotating said shafts, means for intermittently raising each cylinder and actuating each of said heads.

3. In a rotary press, an impression cylinder, a rotatable shaft yieldingly held against said cylinder, a plurality of number cylinders on said shaft, each of said cylinders comprising a plurality of numbering heads symmetrically disposed about said shaft, ratchet mechanisms for intermittently actuating the elements of said numbering heads, a rock shaft for each of said heads and operatively connected to said ratchet mechanisms, a radially swinging rocker arm on each of said shafts, an axially movable tapered collar on said first mentioned shaft for radially swinging said arms to rock said shafts, and means carried by said cylinder 125 for raising said shaft and moving said collar.

4. In a rotary press, an impression cylinder, an operating segment thereon, a plurality of numbering shafts, means for rotating said shafts, a rider on said shafts to 130

- engage said segment for raising said shafts to clear the work, an adjustably mounted numbering cylinder on each shaft, a plurality of intermittently actuated rotatable numbering heads therein, means for actuating said heads while raised from the work.
5. In a rotary press, an impression cylinder, a plurality of shafts yieldingly held against said cylinder, numbering cylinders on said shafts, a plurality of intermittently actuated rotatable numbering heads in each cylinder, means for rotating said shafts, means for intermittently raising each shaft and actuating each of said heads.
10. 6. In a rotary press, an impression cylinder, a rotatable shaft yieldingly held against said cylinder, a plurality of number cylinders, each of said cylinders comprising a plurality of numbering heads symmetrically disposed about said shaft, ratchet mechanisms for intermittently actuating the elements of said numbering heads, a rock shaft for each of said heads and operatively connected to said ratchet mechanisms, a radially 25 movable member for rocking each of said shafts, an axially movable tapered collar on said first mentioned shaft for radially moving said member to rock said shafts, and means carried by said cylinder for raising 30 said shaft and moving said collar.
7. In a rotary press, an impression cylinder, a rotatable shaft, a plurality of number cylinders, each of said cylinders comprising a plurality of rotatable numbering heads disposed about said shaft, ratchet mechanisms for intermittently actuating the elements of said numbering heads, a rock shaft for each of said heads and operatively connected to said ratchet mechanisms, a radially 35 moving member for rocking said shafts, and axially movable means for radially moving said member, an actuating means on said cylinder for moving said means axially.
40. 8. In a device of the class described, a rotatably mounted numbering head, a plurality of rotatable numbering disks therein, radially acting means for intermittently rotating said disks and a member movable axially to actuate said means radially.
9. In a device of the class described, a plurality of rotatably mounted numbering heads, a plurality of rotatable numbering disks in each head,—radially acting means for intermittently actuating each of said heads, and a member movable axially to 55 simultaneously actuate said means radially.
10. In a device of the class described, a rotatably mounted numbering head, a plurality of rotatable numbering disks, pawls for intermittently advancing said disks, a 60 rocker for actuating said pawls, a radially swinging arm on said rocker, and a member movable axially to actuate said arm radially.
11. In a device of the class described, a 65 rotatable shaft, a cylinder comprising a plurality of rotatable numbering heads disposed about said shaft, ratchet mechanisms for intermittently actuating the elements of said numbering heads, a rock shaft for each of 70 said heads, and means for simultaneously actuating said rock shafts to actuate said ratchet mechanisms.
12. In a device of the class described, a 75 rotatable shaft, a cylinder comprising a plurality of rotatable numbering heads disposed about said shaft, radially acting means for actuating the elements of said numbering heads, and means movable axially to actuate simultaneously said radially acting means. 80
13. In a device of the class described, a rotatable shaft, a plurality of cylinders, each of said cylinders comprising a plurality of rotatable numbering heads disposed about said shaft, ratchet mechanisms for intermittently actuating the elements of said numbering heads, a rock shaft for each of said heads and operatively connected to said ratchet mechanisms, a radially swinging rocker arm on each of said shafts, and means 85 movable axially to swing radially said arms to rock said shafts. 90

In testimony whereof, I affix my signature in presence of two witnesses.

WILLIAM FLETT.
